UNITED STATES PATENT OFFICE.

GUSTAVUS A. MANG, OF BUFFALO, NEW YORK.

DESIGN FOR A TWINE-HOLDER.

48,754.

Specification for Design.

Patented Mar. 21, 1916.

Application filed November 19, 1915. Serial No. 62,429. Term of patent 7 years.

To all whom it may concern:

Be it known that I, GUSTAVUS A. MANG, a citizen of the United States of America, and a resident of the city of Buffalo, county of Erie, and State of New York, have invented a new, original, and ornamental Design for Twine-Holders, of which the following is a specification, reference being had to the accompanying drawings, forming a part thereof.

In the drawings, Figure 1 shows a front elevation of a twine holder illustrating my

design; Fig. 2 is a side elevation thereof, and Fig. 3 is a plan view.

I claim:

The ornamental design for a twine holder, as shown.

In testimony whereof, I have hereunto signed my name in the presence of two subscribing witnesses.

GUSTAVUS A. MANG.
